CLAIM

The ornamental design for a blind slat material, as shown and described.

DESCRIPTION

FIG. 1 is a front elevational view of blind slat material showing my new design;

FIG. 2 is a plan view of the top end thereof, the bottom end plan view being identical;

FIG. 3 is a left side elevational view thereof, the right side elevational view being identical;

FIG. 4 is a front enlarged fragmentary view thereof;

FIG. 5 is a rear elevational view thereof; and,

FIG. 6 is a rear enlarged fragmentary view thereof.

The blind slat material is shown broken away in FIGS. 1, 3, and 5, to indicate indeterminate length.
